J. A. SHARP.

GRAIN BINDER.

APPLICATION FILED JAN. 10, 1913.

1,113,697.

Patented Oct. 13, 1914.

UNITED STATES PATENT OFFICE.

JAMES A. SHARP, OF SPRINGFIELD, OHIO, ASSIGNOR TO INTERNATIONAL HARVESTER COMPANY, A CORPORATION OF NEW JERSEY.

GRAIN-BINDER.

1,113,697.

Specification of Letters Patent.

Patented Oct. 13, 1914.

Application filed January 10, 1913. Serial No. 741,328.

To all whom it may concern:

Be it known that I, JAMES A. SHARP, a citizen of the United States, residing at Springfield, in the county of Clark and 5 State of Ohio, have invented certain new and useful Improvements in Grain-Binders, of which the following is a full, clear, and exact specification.

My invention relates to grain binders, and 10 in particular to an improved stop dog mechanism forming part of the needle and knotter actuating means; the object of my invention being to provide a stop dog which is simple in construction, has a great degree 15 of flexibility, and is efficient in operation. I attain these objects by means of the mechanism, one embodiment of which is illustrated in the accompanying drawing, in which—the figure is a view in perspective of 20 a part of a grain binder having my invention embodied in the construction thereof.

1 represents the end member of the binder frame, 2 the lower arm, having the needle shaft 3 journaled therein, and 4 represents 25 laterally extending ear members integral with said arm and having the compressor shaft 5 journaled thereon.

6 represents the trip arm at one end of a trip shaft (not shown), and 7 represents the 30 clutch tripping arm at the opposite end of the shaft that is in engagement with the clutch pawl 8.

9 represents the knotter actuating shaft having the cam gear wheel 10 secured thereto, and 11 represents the pitman connecting the cam gear with the crank arm 12 of the 35 needle shaft 3.

Carried by one end of the compressor shaft 5 is the usual compressing arm 13, and 40 secured to the opposite end of said shaft is an arm 14.

15 represents a common form of cam integral with the wheel 10, 16 a lever pivotally mounted upon the binder frame and having 45 a roller 17 journaled upon one end thereof and adapted to engage with the cam 15, and 18 represents a link connection between the opposite end of said lever and the arm 14.

All of the parts as enumerated above are 50 common in the class of machines indicated and are not of my invention.

In the operation of machines of this character it is usual to provide means for turning the cam wheel a little beyond the limit 55 imparted to it by the driving mechanism,

and for that purpose a spring-pressed dog is frequently used that engages with a cam surface upon the cam wheel in a manner to turn it beyond its limit and to resist a retrograde movement thereof. In my invention the arm 14 is provided with a bracket member 19, that includes a barrel-like member 20 arranged at right angles with the axis of the compression shaft, having a plunger 21 slidably mounted therein, said plunger 60 being provided with a reduced portion that receives a compression spring 22, operative between one end of the barrel portion and the plunger in a manner to project the plunger beyond the opposite end of the barrel, 65 whereby it will contact with a fixed part of the frame of the machine and yieldingly rock the compressor shaft and, through the pitman connection between the arm 14 and the lever 16, bring the cam gear wheel 10 to 70 its position of rest at the end of the operative movement thereof. 75

While I have described in this application one embodiment which my invention may assume in practice, it is, of course, to be understood that the form shown herein is used for purposes of illustration and may be modified without departing from the spirit of the invention. 80

What I claim as my invention, and desire 85 to secure by Letters Patent, is:

1. A grain binder having, in combination, a compressor mechanism including a rock shaft, a rotatable member connected with said shaft and adapted to rock it in a compressing direction, and yielding means for 90 rocking said shaft in an opposite direction and controlling an angular movement of said rotatable member at a predetermined part thereof. 95

2. A grain binder having, in combination, a main frame, a compressor mechanism including a rotatable cam gear and a rock shaft, an operative connection between said gear and said shaft, and a spring mechanism for rocking said shaft in a direction 100 controlling an angular movement of said gear at a predetermined part thereof.

3. A grain binder having, in combination, a main frame, a compressor mechanism including a rotatable cam gear and a rock shaft, an operative connection between said gear and said shaft, and a spring mechanism carried by said shaft for rocking said shaft in a direction controlling an angular 105 110

movement of said gear at a predetermined part thereof.

4. A grain binder having, in combination, a main frame, a knotter actuating shaft journaled in said frame, a cam gear wheel secured to said shaft, a lever pivotally mounted upon said frame and having one end thereof engaging with said cam wheel, a compressor shaft journaled in bearings carried by said frame, an arm secured to said shaft, a pitman connection between said arm and said lever, and a spring mechanism carried by said compressor shaft and adapted to engage with a fixed part of said main frame during a part of the operative movement of said compressor shaft.

5. A grain binder having, in combination, a main frame, a knotter actuating shaft journaled in said frame, a cam gear wheel secured to said shaft, a lever pivotally mounted upon said frame and having one end thereof engaging with said cam wheel, a compressor shaft journaled in bearings carried by said frame, an arm secured to said shaft, a pitman connection between said arm and said lever, and a spring-pressed plunger slidably mounted upon said

compressor shaft and adapted to engage with said main frame during a part of the operative movement of said compressor shaft.

6. A grain binder having, in combination, a main frame, a knotter actuating shaft journaled in said frame, a cam gear wheel secured to said shaft, a lever pivotally mounted upon said frame and having one end thereof engaging with said cam wheel, a compressor shaft journaled in bearings carried by said frame, an arm secured to said shaft, a pitman connection between said arm and said lever, a bracket member forming part of said arm, and a spring-pressed plunger carried by said bracket, arranged transversely relative to the axis of said compressor shaft and adapted to engage with said main frame during a part of the operative movement of said shaft.

Chicago, Ill., Dec. 31, 1912.

In testimony whereof I affix my signature, in the presence of two witnesses.

JAMES A. SHARP.
